(57) **CLAIM**

The ornamental design for an electrical pole as shown and described.

DESCRIPTION

FIG. 1 is a top perspective view of an electrical pole, showing our new design;

FIG. 2 is a front elevation view thereof;

FIG. 3 is a right-side elevation view thereof;

FIG. 4 is a rear elevation view thereof;

FIG. 5 is left side elevation view thereof;

FIG. 6 is a top plan view thereof;

FIG. 7 is a bottom plan view thereof;

FIG. 8 is a top perspective view of a second embodiment of an electrical pole, showing our new design;

FIG. 9 is a front elevation view thereof;

FIG. 10 is a right-side elevation view thereof;

FIG. 11 is a rear elevation view thereof;

FIG. 12 is left side elevation view thereof;

FIG. 13 is a top plan view thereof; and,

FIG. 14 is a bottom plan view thereof.

The claimed design is shown with a symbolic break in its length, the appearance of any portion of the article between the break lines forms no part of the claimed design.

1 Claim, 8 Drawing Sheets
